UNITED STATES PATENT OFFICE.

JOHN M. STOKOE, OF CLEVELAND, OHIO.

DESIGN FOR A HEATING-STOVE.

No. 37,530.

Specification for Design.

Patented Sept. 5, 1905.

Application filed July 26, 1905. Serial No. 271,376. Term of patent 7 years.

To all whom it may concern:

Be it known that I, JOHN M. STOKOE, a citizen of the United States, residing at Cleveland, in the county of Cuyahoga and State of Ohio, have invented a new, original, and ornamental Design for Heating-Stoves, of which the following is a specification, reference being had to the accompanying drawing, forming part thereof.

The figure is an elevation of a heating-stove, showing my new design.

I claim—

The ornamental design for a heating-stove, as shown.

JOHN M. STOKOE.
